(57) CLAIM

The ornamental design for a fireplace tool stand, as shown and described.

DESCRIPTION

FIGS. 1 and 2 are perspective views of a fireplace tool stand showing our new design;

FIG. 3 is a front view thereof, the back view being identical; FIG. 4 is a right side view thereof, the opposing left side view being identical;

FIG. 5 is a top view thereof; and,

FIG. 6 is a bottom view thereof.

The broken lines shown in the drawings are included for purposes of illustrating portions of the fireplace tool stand and form no part of the claimed design. The fireplace tools shown in broken lines in FIG. 1 are included for purposes of illustrating environment and form no part of the claimed design.
